UNITED STATES PATENT OFFICE.

NORMAN T. MACFERRON, OF ALLEGHENY, PENNSYLVANIA.

DESIGN FOR A SOUVENIR SPOON.

SPECIFICATION forming part of Design No. 28,154, dated January 11, 1898.

Application filed October 14, 1896. Serial No. 608,896. Term of patent 31 years.

To all whom it may concern:

Be it known that I, NORMAN T. MACFERRON, a citizen of the United States, residing at Allegheny, in the county of Allegheny and State of Pennsylvania, have invented and produced 5 a new and original Design for Souvenir Spoons, of which the following is a clear and exact description, reference being had to the accompanying drawings, showing the parts thereof.

Figure 1 is a front view showing the obverse of the spoon, and Fig. 2 a rear view showing the reverse of the same.

In the bowl of the spoon are the portraits 1 and 2 of McKinley and Hobart. Immediately above these portraits is the representation 3 of an eagle having outspread wings which arch over said portraits. Said eagle is at the extreme upper end of the spoon-bowl. On the spoon-handle, immediately above the 20 eagle, is a star 5. The top of the handle is provided with the representation 8 of the Na-

tional Capitol building. The upper end of the spoon is fluted, as at 9, to give the appearance of a series of rays emanating from the representation 8. Immediately below the 25 representation 8 are the representations of two pieces of goldenrod 10 and 11, which are shown crossed.

The foregoing is that of the obverse of the spoon. 30

The reverse of the upper end of the handle bears the representation 12 of the corner-post of a fence, on which is perched a "coon" 13.

Having thus particularly pointed out the features of my design, what I claim is— 35

The design for a spoon, substantially as herein shown and described.

NORMAN T. MACFERRON.
